TRAY

Patricia A. Antoni, Wheeling, Ill., assignor to Ekco Products, Inc., Wheeling, Ill.

Filed Feb. 3, 1971, Ser. No. 112,504

Term of patent 14 years

Int. Cl. D7—01

U.S. Cl. D44—10

FIG. 1 is a top plan view of a tray showing my new design.

FIG. 2 is an elevational view thereof taken along line 2—2 of FIG. 1.

FIG. 3 is a cross-sectional view taken along line 3—3 of FIG. 1.

I claim:

The ornamental design for a tray, as shown.
